UNITED STATES PATENT OFFICE.

OTTO J. MULLER, OF NEW YORK, N. Y., ASSIGNOR OF ONE-HALF TO LADISLAV KAPLAN,
OF CLINTON, CONNECTICUT.

SECURING MEANS FOR THE ENDS OF STRINGS FOR INSTRUMENTS.

1,363,902.

Specification of Letters Patent. Patented Dec. 28, 1920.

Application filed April 30, 1919. Serial No. 293,627.

To all whom it may concern:

Be it known that I, OTTO J. MULLER, a citizen of the United States, and a resident of the city of New York, borough of Manhattan, in the county and State of New York, have invented new and Improved Securing Means for the Ends of Strings for Instruments, of which the following is a full, clear, and exact description.

This invention relates to an anchor for the end of a string adapted to be used in connection with musical instruments.

It is well known that considerable difficulty has been experienced in threading the ends of strings for musical instruments through the rotatable keys adapted to receive them; and this has been more particularly true in connection with strings adapted for use on the violin, of which probably the metallic "E" string may be numbered among the most difficult strings to properly thread.

To facilitate the application of the end of a string to a key, I have devised a simple form of anchoring means adapted to be applied to such end and to engage the key of an instrument so that the string may be applied to the key with the loss of only an instant of time.

Reference is had to the accompanying drawings which illustrate one practical embodiment of my invention, and in which—

Figure 1 is a side elevation of a key having applied to it a metallic "E" string to whose end is secured my improved anchoring device; and

Fig. 2 is an enlarged view illustrating such anchoring device.

In these two figures, the reference numeral 1 designates a key provided with a transverse bore 2 in the usual manner. A pin, formed preferably with a tapered shank 3, projects into the bore 2, a groove 4 being formed below the head 5 by virtue of an annular shoulder 6 extending around the upper portion of the shank 3 and spaced from the head 5.

A string 7, which may be formed with twisted and silk-wound ends 8, has one of

its ends seating within the groove 4 and around the shank 3. 50

It will now be seen that by virtue of the tapered shank 3, to which the string 7 is secured, the end of the said string may be quickly and securely applied to any key, such as 1. Further, the provision of the shoulder 6 makes it impossible for the shank 3 to slide too far within the bore 2, as well as preventing the displacement of the looped end of the string 7 from the shank 3, this displacement being also effectually guarded 60 against at the upper end of the shank by means of the head 5.

I wish it understood that although I have shown the shank 3, in its associated parts, applied to a metallic "E" string for a violin, the same is equally applicable to any of the strings of a violin, and might, for that matter, readily be used in connection with the strings of any musical instrument, such as a piano or a harp, as with this device the 70 strings may easily be applied to keys without any danger of their being accidentally displaced. In fact, the shank 3 in its component parts might be applicable for the securing of the looped end of any string 75 within any opening.

Having thus described my invention, I claim as new and desire to secure by Letters Patent:

1. As an article of manufacture, an instrument string, a pin formed with a groove adjacent one of its ends, one of the ends of said instrument string being permanently secured to said pin, and seating within said groove. 80

2. As an article of manufacture, an instrument string, a pin formed with a groove adjacent one of its ends, one of the ends of said instrument string being permanently secured to said pin and seating within said 90 groove, said pin being formed with a tapered shank adapted to afford a removable connection between said pin and the transverse bore of an instrument key. 85

OTTO J. MULLER.
